UNITED STATES PATENT OFFICE.

EDWARD C. WARD, OF VALLEY FALLS, NEW YORK, ASSIGNOR TO ABRAHAM LAPOVSKY, OF NEW YORK, N. Y.

KNITTED FABRIC.

Application filed September 17, 1921. Serial No. 501,285.

To all whom it may concern:

Be it known that EDWARD C. WARD, citizen of the United States, residing at Valley Falls, in the county of Rensselaer and State of New York, has invented certain new and useful Improvements in Knitted Fabrics, of which the following is a specification.

This invention relates to knitted fabrics, and has for one of its objects the provisions of knit goods having closely knitted and contiguous openly knitted portions arranged alternately throughout the width of the fabric and having each of said portions continuous throughout the length of the piece of goods.

A further object of this invention is the provision of knit goods of the kind above described wherein the openly knitted portion is equally spaced with close knitted ribbed portions.

More particularly this invention has for its object the provision of a knitted goods whereby a closely knitted portion commonly known as taffeta stitching and an openly knitted portion equally spaced with ribs therein known as rib stitching form a fabric possessing durability and being neat in design and pleasing in appearance.

A still further object of this invention is the provision of a knitted fabric of good appearance capable of being economically manufactured in which the design may be varied as desired widthwise of the piece of goods.

Other objects of this invention will in part be obvious and in part hereinafter pointed out.

Certain features herein shown and described are shown, described, and claimed in my co-pending application for patent Serial No. 501,284 filed in the United States Patent Office.

The invention accordingly consists in the features of construction, combinations of elements and arrangement of parts which will be exemplified in the construction hereinafter described and of which the scope of application will be indicated in the following claims.

In the accompanying drawings in which is shown one of various possible illustrative embodiments of this invention,

Fig. 1 is a front view of one type of my improved fabric, the thicknesses of the

threads being exaggerated for the sake of clarity.

Fig. 2 is a diagrammatic top plan view of the guides carried by the usual guide bars, and of the needles of a knitting machine showing the method of threading the machine and indicating the paths of the horizontal motion of the guide bars; and

Fig. 3 is an enlarged view of a piece of fabric knitted by means of my improved method, showing the stitching in detail.

In the practical embodiment of my invention, I produce the fabric 11 comprising a series of closely knitted portions 10 commonly known as taffeta stitching combined with the openly knitted portion 12, said openly knitted portions being equally spaced and divided as at 14—14 by ribs 13 13'. The closely knitted portion and the openly knitted portion spaced as shown in Fig. 1 alternate contiguously widthwise of the fabric.

Said portions 10 are formed by threading the warp and thread guides 15 with threads as 16, said guides being carried by the usual guide bars, while warp threads as 18 are carried by their corresponding guides 17 in the manner usual with a machine of this character in which needles 19 of the usual type are provided.

Referring to Fig. 1 it will be noted that the piece of fabric illustrated consists of two closely knitted portions 10 with a loosely knitted portion 12 in between having ribs 13 formed thereon in a manner to be hereinafter described. The width of the fabric is from left to right, while the length of the piece is measured vertically from the upper to the lower edge, so that said portions 10 and 12 preferably run continuously throughout the length. It will be understood, however, that any number of alternately arranged closely knitted portions or taffeta stitching and loosely knitted portions having ribs thereon may be produced

in the width of the fabric by providing the desired number of needles widthwise. Furthermore, the spacing of the closely knitted and loosely knitted portion may also be varied by varying the number of needles and guide provided for each of these portions while the widths of the ribs and the widths of the loosely knitted portion between two adjacent ribs may likewise be varied as will hereinafter become evident.

The fabric will be described in connection

with the simple chain stitch but any other desired stitch may be employed.

Referring to Figs. 2 and 3 of the drawing, the warp thread 16 carried by the guides 5 15 engage the needle 19 forming the loop 20. The guides 15 then direct the travel of thread 16 to the right adjacent needle as shown at 21 for engagement therewith to form the loop 22 and then thread 16 travels 10 back to the left as at 23 and engages the adjacent needle 19 and again commences this cycle of motion forming the loop 24 beneath the loop 20, etc. All the threads of the guide 15 and the needles 19 in the width of the 15 closely knitted portion of the knitting machine simultaneously produce this cycle of motion for the length of the fabric desired. The guides 17 operate simultaneously with the guides 15 and the threads 18 carried by 20 them interlock the threads 16 to form the closely knitted taffeta stitched portion 10 of the fabric 11. The thread 18 having the loop 25 formed thereon from its last engagement with the needle 19 interlocks 25 the thread 16 as shown at 26 and is directed by its corresponding guide 17 to travel to the right as 27 to the second adjacent needle for engagement therewith to form the loop 28 and then travels to the 30 left, as at 29 to the second adjacent needle for engagement therewith to form the loop and continues the cycle of motion operation already described. The guides 17, threads 18 and needles 19 in that width of the knitting 35 machine devoted to the closely knitted or taffeta stitched portion operate simultaneously, and the guide bar carrying the guides 17 operates simultaneously with the guide bar carrying the guides 15. In Fig. 3 40 the actual stitch made by each of the threads is shown enlarged as well as the interlocking between the threads producing an integral closely knitted portion 10. Fig. 2 diagrammatically indicates the path of 45 motion of the threads, the full lines referring to the threads 16 and dotted lines referring to the threads 18.

For the sake of brevity, I will confine my 50 description of the loosely knitted portion 12 to the section 14 and the rib 13 thereon. This portion 12 of my fabric 11 is formed simultaneously with the closely knitted portions 10 and with the same motion of the guides. I obtain my loosely knitted portions 55 by omitting to thread every other two guides 30, thus the width of the section 14-14' is equivalent to the distance bridged by four consecutive guides. To obtain the loosely knitted sections 14 of the portion 60 11, I employ the warp thread 18 threaded in the guide 17 as already described. I do not interlock my thread 18 with the warp thread 16 as in my closely knitted portion 10 but omit it entirely. This is shown in Fig. 3 65 where I indicate by the letter A the loosely

knitted section 14 between the right extremity of the closely knitted portion 10 and the first rib stitching 13. The rib section 13 is produced by a thread comprising four strands as indicated in Fig. 2 threaded in 70 the guide 15 and actuated by the guide bar carrying these guides. The thread 31 guided by its guide 15 engages a needle 19 forming the loop 32 then is guided to the right as at 33 to the adjacent needle for engagement 75 therewith, thus forming the loop 34 and then travels to the left as at 35 engaging the adjacent needle and forming the loop 36, etc., continuing the desired length of the fabric. The thread 31 interlocks with the thread 18 80 to form the stitching commonly known as rib stitching. The width of the rib section 13 in the embodiment of my invention illustrated in the drawings is therefore seen to comprise two threads 31 of four strands 85 each and the singly stranded thread 18 or 9 threads in all.

The number of these loosely knitted sections 14-14' and rib sections 13, 13' that may enter into my alternating openly 90 knitted portion may be varied by various changes in the number of guides employed. Furthermore, the design may be changed to various patterns by omitting to thread the guides in other series than each alternating 95 two, or by assembling more than two threads and guides to make the rib section.

By varying the amount of transverse movement of the guide bar, by changing the 100 number of said guide bars by changing the relative spacing or gauge of the effective needles various designs other than those illustrated may be made and variously colored threads may be worked into a suitable design.

It will thus be seen that there is provided a method in which the several objects of this invention are achieved and which is well adapted to meet the conditions of practical use.

As various possible embodiments might be made of the above invention and as various changes might be made in the embodiments above set forth, it is to be understood that all matter herein set forth or shown in the accompanying drawings is to be interpreted 115 as illustrative and not in a limiting sense.

Having thus described my invention, I claim as new and desire to secure by Letters Patent:—

1. A piece of knit goods comprising contiguous longitudinal band of taffeta stitching arranged alternately throughout the width of the goods with longitudinal loosely knitted portions having rib stitching arranged thereon.

2. In a piece of knit goods, a closely knitted portion comprising two series of looped warp threads interlocking each other, a loosely knitted portion formed by omitting

posed in the horizontal plane of the upper surface of the undepressed longitudinal member.

7. A motor vehicle frame comprising a pair of oppositely disposed longitudinal members in the same horizontal plane except for an intermediate portion of one of said members being depressed below the level of the corresponding portion of the other member, and cross members connecting said longitudinal members at the depressed portion and having openings for the power shaft of the vehicle.

8. A motor vehicle frame comprising a pair of oppositely disposed longitudinal members in the same horizontal plane except for an intermediate portion of one of said members being depressed below the level of the corresponding portion of the other member, cross members connecting said longitudinal members at both elevated and depressed portions, the latter cross members being straight and disposed in the plane of the undepressed member and resting upon the depressed member, a platform carried by the depressed portion of the depressed longitudinal and by the lower portions of the

latter cross members, and a floor carried by the upper surfaces of the undepressed portions of the longitudinals and of the cross members.

9. A motor vehicle chassis, comprising a pair of forward wheels, a pair of rear wheels, axles connecting the wheels of said respective pairs, a frame having a pair of longitudinal members connected by cross members and supported by said axles, said frame being positioned between the wheels of said respective pairs and one of its longitudinal members having a portion between the forward and rear axles depressed below the level of the corresponding portion of the other longitudinal member, a floor carried on said frame and overhanging the same on either side, and a lowered entrance platform carried by the depressed member, and extending both outwardly therefrom and inwardly substantially to the center-line of the vehicle.

Signed at New York, in the county of New York and State of New York this 18th day of November A. D. 1921.

CLAUDE A. WALES.
